ORNAMENTAL BUTTON ASSEMBLY

Walter I. Jones, Belmont, Mass., assignor to
 United-Carr Fastener Corporation, Cambridge,
 Mass., a corporation of Massachusetts

Application December 6, 1946, Serial No. 714,413

1 Claim. (Cl. 24—1)

1

The present invention relates to ornamental button assemblies, such as those employed in wearing apparel, and aims to provide simplified means for attaching the button or ornamental part to a supporting material. The word buttons is given a broad scope so as to include button parts of snap fasteners.

More particularly, my invention relates to a novel means and manner of attaching an ornamental or like button to an attaching plate, which may, if desired, be one of the parts of co-operating stud and socket snap fastening members.

The above and other objects of the invention will be apparent to persons skilled in the art from a consideration of the accompanying drawings and annexed specification illustrating and describing preferred embodiments.

In the drawings

Fig. 1 is a plan view of one form of ornamental fastener assembly as shown applied to a fragmentary portion of a supporting member such as an article of wearing apparel;

Fig. 2 is a side view of the ornamental fastener shown in Fig. 1;

Fig. 3 is an enlarged sectional view as taken on the line 3—3 of Fig. 1;

Fig. 4 is a perspective view of the attaching plate;

Fig. 5 is an enlarged sectional view of an ornamental stud fastener member embodying the invention;

Fig. 6 is an enlarged sectional view of an ornamental socket fastener member embodying the invention;

Fig. 7 is a detail perspective view of the button attaching plate shown in Fig. 6; and

Fig. 8 is an enlarged sectional view of another form of ornamental socket fastener member embodying the invention.

The invention provides simple and novel means for attaching an ornamental button and the like to a piece of supporting material, either as a purely decorative feature or as a decorative attachment of a stud and socket snap fastener. The ornamental part of the button 1 may be of any desired shape and configuration having a substantially plane surface 2 and a convexed outer surface 3. It may be formed of any desired material, such as metal, bone, pearl, synthetic plastic or the like, and for purposes of illustration may be of ring-like or annulus form providing a central aperture 4, the surface 3 being convexed between the outer and inner peripheral walls.

2

The ornamental part or button 1 may be a decorative ornament secured to a piece of supporting material 5, which may be an article of wearing apparel, for example, a glove, as shown in Figs. 1 to 5. According to this form of the invention, the part 1 may be secured to the supporting material 5 with the plane surface 2 in contact with the material 5, by means of a single attaching plate 10 disposed on the opposite side of the material and formed with material-penetrating and article-gripping prongs 11. The attaching plate 10 is conveniently in the form of a ring of sheet material, for example, metal or sheet synthetic plastic. The prongs 11 preferably taper toward pointed ends 12 capable of smoothly penetrating the material of the support 5 and of being bent into engagement with and overlying a portion of the convexed surface 3 of the ornamental part 1. It will be understood that the material of the attaching plate 10 will have sufficient stiffness to permit the prongs to retain their deformed shape in which the effective diameter and the pointed ends 12 are substantially different from the diameter of that edge of plane surface 2 engaged by the prongs 11 to secure the part 1 thereto. Preferably, the prongs 11 are formed of and extend from the inner peripheral edge of the attaching plate 10 and are bent over the convexed surface 3 of the part 1 adjacent the opening 4 thereof. With this arrangement, when five prongs are employed, they produce a star-shaped effect within the margins of the ornamental button as indicated in Fig. 1.

The ornamental part 1 and the novel attaching means therefor, as above described, may be embodied in the cooperating stud and socket parts of a snap fastener as shown in Figs. 5 and 6.

In Fig. 5 the attaching plate 10^a is similar to that shown in Fig. 4 but is provided with an annular skirt or flange 15 extending from the outer peripheral edge of the base as shown in Fig. 7. This skirt or flange 15 is adapted to be turned over a disc 16 forming the base of stud member which is provided with a bulbous head 17 adapted for snap fastener locking engagement with a suitable socket device. By reason of the skirt 15, the plate 10^a and base 16 may be securely connected together to form a unitary part having a snap fastener stud 17 on one face thereof, and ornament-attaching prongs 11^a extending from an opposite face thereof.

Similarly, as shown in Fig. 6, the ornament 1 may be secured to the supporting fabric 5 by means of a pronged attaching plate 10^a as disclosed in Figs. 1 to 4, and a snap fastener socket

member 20 may be attached to the plate 10^a by means of a skirt 15 extending from the plate 10^a as above described and as shown in Fig. 7.

The socket member 20 preferably comprises a central open-ended stud-receiving barrel 21 which may be slotted as at 22 from its outer end to near its base 23 to provide resilience for snap fastener engagement with a stud, for example, such as the stud 17, Fig. 5. The base 23 merges into an outwardly inclined flange 24 surrounding the barrel 21, the peripheral portion of the flange being reversely bent to provide a retainer ring 25 having its free edge spaced from the adjacent surface of the inclined flange. This type of socket member is well known to the snap fastener trade.

The socket member 20 may have, associated therewith, a part 26 presenting a lateral flange 27 adapted for bearing engagement with and attached to the base plate of the attaching member 10. The part 26 may be a part like the attaching member 10 (Fig. 4), the prongs 28 of which are curled within the retainer ring 25. The attaching member for securing the ornamental part 1 to the supporting material 5 is preferably of the same form as shown in Figs. 5 and 7 in that the base flange 10^a is formed with a peripheral flange or skirt 15 adapted to be turned over the flange 27 to secure the parts together.

In Fig. 8 I have illustrated an alternative form of socket fastener member embodied in a somewhat different form of stud-receiving socket. In this construction the socket part 20^a has a stud-receiving barrel 21^a projecting outwardly from a plane base plate 22^a disposed in a plane normal to the axis of the barrel 21^a. In such form the skirt 15 of the attaching member 10^a may be directly turned over the base 22^a of the socket part 20^a, thus simplifying the construction.

From the above, it will be seen that the invention provides an attractive and decorative ornamental fastener or button assembly suitable for decorating articles of wearing apparel, such as gloves, hats, shoes, belts and the like. The ornamental part 1 may be open or ring-like in

form, in which case the central aperture is bridged by a section of supporting material. The only portion of the attaching means, viewed from the exposed side of the material on which the part 1 is positioned, is the pointed ends of the attaching prongs, which, when five in number and bent over the inner convexed surface of the part 1, produce an attractive star design as illustrated in Fig. 1.

10 Although I have described my invention with particular reference to several specific embodiments of the invention, it is to be understood that it is not limited thereto, as the scope of the invention is best defined by the appended claim.

15 I claim:

20 A decorative button assembly for articles of wearing apparel and the like comprising a ring-like ornamental part having an outer peripheral edge, an inner peripheral edge surrounding a central opening of said part, an outer surface between said edges and an inner flat surface between said edges, and fastener means for attaching said part directly to a supporting material comprising a ring-like base element having outer 25 and inner peripheral edges and a plurality of support-penetrating prongs extending angularly to said base from the inner peripheral edge thereof, said base element underlying said inner flat surface of said ring-like part, said prongs 30 extending within said central opening of said ring-like part and engaging over portions of said outer surface of said part for clamping a supporting material between said base and said inner flat surface.

35 WALTER I. JONES.
